UNITED STATES PATENT OFFICE

ADRIAN O. ABBOTT, JR., OF DETROIT, MICHIGAN, ASSIGNOR TO MORGAN & WRIGHT, OF DETROIT, MICHIGAN, A CORPORATION OF MICHIGAN

APPARATUS FOR SHAPING FLAT-BUILT CASINGS

Application filed February 26, 1929. Serial No. 342,875.

This invention relates to a device for expanding pulley bands into the form of a tire casing.

In building automobile tire casings it is usual to assemble the constituent parts of the casing on a drum having a flat face so as to form an endless band known in the art as a pulley band. The pulley band is shaped into the form of a tire casing by what is known as a vacuum box which consists of a circularly shaped hollow box provided with apertures to receive a pulley band and the interior of which is connected with a device for reducing fluid pressure. The reduction of the fluid pressure within the vacuum box results in a differential pressure acting upon the pulley band due to the atmospheric pressure which causes the pulley band to expand into the vacuum box and into the shape of a tire casing. The apertures which are provided to permit the ready insertion of the pulley band into the vacuum box are of a diameter larger than the outside diameter of the pulley band in order that the pulley band may be readily inserted. In order that the device for reducing pressure within the vacuum box may be effective, it is necessary to provide some means to effect a preliminary seal between the vacuum box and the pulley band so that a differential pressure may be set up upon the operation of the pressure reducing device.

It is the object of this invention to provide a new and improved device for effecting the seal between a vacuum box and a pulley band inserted therein. It is also the object of this invention to provide a preliminary sealing device for a vacuum box in the form of a member slidably arranged in sealing engagement with the top and bottom plates of the vacuum box and so constructed that upon movement of the member into contact with the pulley band a seal between the pulley band and the member will be effected on one side and a seal between the pulley band and the margin of the aperture will be effected on the other side of the band. Other objects and advantages of the present invention will appear in the following detailed descriptions

taken in connection with the accompanying drawings in which:

Fig. 1 is a plan view of a preferred form of my invention.

Fig. 2 is a diagrammatical cross sectional view of the device shown in Fig. 1.

Referring to the drawing the vacuum box 1 consists of the bottom plate 2 and annular side 3 integral therewith to which is hingedly fixed as indicated at 4 the top plate 5 which is arranged to open and close the casing. A suitable gasket 6 is provided between the top plate 5 and side wall 3 to render the seal therebetween substantially air-tight. An aperture 7 is provided in each of the bottom plate 2 and the top plate 5. The vacuum box is mounted upon a suitable pedestal 8. The pedestal 8 forms a platform upon which the lower edge of the pulley band rests when it is first inserted within the vacuum box and the vacuum box is positioned at a distance from the pedestal such that the pulley band will be properly centered with respect to the vacuum box when it is first inserted therein. Suitable pipe connections 9 lead from the interior of the vacuum box to any suitable means for reducing the pressure within the vacuum box such as a pump.

In order to effect a preliminary seal between the vacuum box and the pulley band a slidible member or plate 10 is mounted upon the top and bottom plates 2 and 5, preferably being pivoted thereto by any suitable means such as pins 11. In order to maintain an air-tight seal between the slidible arms 10 and the top and bottom plates 2 and 5, a gasket or sheet 12 of rubber or leather or similar material is provided between the sliding members 10 and the top and bottom plates 2 and 5. This gasket or sheet 12 may be secured to the top and bottom plates 2 and 5 in any suitable manner such as by cementing. That slidible plate which is mounted upon the bottom plate 2 of the vacuum box is provided with an upstanding arm 13 which is forked at its upper end as indicated at 14. That slidible member 10 which is mounted upon the top plate 5 is provided with a lug 15 which extends between the tines of the fork 14. The slidible plate 10 which is mounted

upon the top plate 5 of the vacuum box is provided with a suitable manipulating handle 16 and upon movement of that slidable member 10 a corresponding movement of the slidable plate 10 mounted upon the bottom plate 2 of the vacuum box is effected, due to the connection between the two slidable plates provided by the yoke 14 and the lug 15. While the slidable members 10 have been described as being pivotally mounted upon the top and bottom plates 2 and 5 of the vacuum box, they may be mounted upon the top and bottom plates of the vacuum box in any other suitable manner so long as the sliding engagement therewith is maintained. For instance a pin and slot connection permitting sliding movement may be provided between the sliding members 10 and top and bottom plates 2 and 5. Also the interconnecting means between the top and bottom sliding members 10 may be other than the lug and yoke construction hereinabove disclosed, or the top and bottom slidable members 10 may be independently movable. It is to be noted that the present lug and slot connection between the top and bottom sliding plates 10 permits the top plate 5 or vacuum box to be lifted so as to open the vacuum box and to permit the formed tire casing to be removed therefrom. Although the apertures 7 provided in the top and bottom plates 2 and 5 are normally circular and may be so shaped in the present instance, it is preferred to provide oval apertures for a reason which will appear in the following description.

In the operation of the hereinabove disclosed device, a pulley band 17 is inserted through the apertures 7 of the top and bottom plates of the vacuum box and allowed to rest upon the top of pedestal 8. During the insertion of the pulley band the slidable plates 10 are in the position shown in full lines in Fig. 1. In order to effect a seal between the pulley band and the vacuum box, the slidable plates 10 are manipulated so as to be moved into contact with the pulley band 17. As the slidable plates 10 contact with the pulley band that side of the pulley band opposite the slidable plate 10 is thrust into contact with the margins defining the apertures 7 which effects a seal between such margins and that portion of the pulley band in contact therewith. The contact between the movable arms or plates 10 extends around the pulley band and forms a seal therebetween throughout a distance sufficient to complete the seal around the entire circumference of the pulley band. When the preliminary seal has been formed between the vacuum box and the pulley band as just described, an evacuating means is set into operation so as to reduce the fluid pressure within the vacuum box thereby building up a differential pressure due to atmospheric pressure which causes the pulley band to be expanded

and forced within the vacuum box thereby shaping the same into a tire casing. The edges of the apertures 7 form the final seal between the vacuum box and the pulley band as the expansion of the pulley band progresses. As will be apparent from the above description of the operation, it is of some advantage to have the aperture 7 of an oval shape which permits the pulley band to be readily inserted therein and yet when the pulley band is thrust against the margin bounding the aperture a seal between the pulley band and the margin will be readily effected. However, such a seal is satisfactorily formed even though the apertures 7 are circular due to the flexibility of the pulley band which permits it to accommodate itself to the contour of the margins determining the apertures.

A curing bag is inserted within the shaped tire casing while it is in the vacuum box. Clamping rings or a bull ring are applied to the beads of the casing, the top plate 5 is lifted so as to open the vacuum box and the tire casing containing the curing bag is removed from the vacuum box. The top plate 5 may be lowered and the sliding plates 10 moved into the position shown in full lines in Fig. 1, whereupon the cycle of operations may be repeated.

While one form of the invention has been specifically described and shown, it is obvious to one skilled in the art that many modifications in the details of construction and materials employed may be made which are within the spirit and scope of the invention, all of which modifications are intended to be within the present invention insofar as they are included within the scope of the following claims:

Having thus described my invention, what I claim and desire to protect by Letters Patent is:

1. A vacuum box having top and bottom plates provided with apertures to receive a pulley band, a curved arm slidably mounted on each of said top and bottom plates and in sealed engagement therewith, the curvature and arrangement of each arm being such that upon movement of the arm into contact with a pulley band positioned in the vacuum box a seal is formed between the arm and a circumferential portion of the pulley band and between the margin of the aperture and the remaining circumferential portion of the pulley band, and a mechanical connection between said arms.

2. A shaping box having top and bottom plates provided with apertures to receive a pulley band, a curved arm pivotally mounted on each of said top and bottom plates and in sealing engagement therewith, the curvature and arrangement of each arm being such that upon movement of the arm into contact with a pulley band positioned in the shaping box a

5 seal is formed between the arm and a circumferential portion of the pulley band and between the margin of the aperture and the remaining circumferential portion of the pulley band, and a mechanical connection between said arms.

10 3. A shaping box having top and bottom plates provided with apertures to receive a pulley band, a curved arm pivotally mounted on each of said top and bottom plates and in sealed engagement therewith, one of said arms having a tail piece terminating in a bifurcated portion and the other of said arms having a tail piece fitting in said bifurcation, 15 the curvature and arrangement of each arm being such that upon movement of the arm into contact with a pulley band positioned in the shaping box a seal is formed between the arm and a circumferential portion of the 20 pulley band and between the margin of the aperture and the remaining circumferential portion of the pulley band.

25 4. A shaping box comprising top and bottom plates provided with apertures to receive a pulley band, one of said plates being hingedly mounted, a curved arm pivotally mounted on each of said top and bottom plates and in sealed engagement therewith, a tail piece on one of said arms extending across 30 said box between said plates and terminating in means for engaging a tail piece on the other arm, and a tail piece on said other arm cooperating with said engaging means.

35 5. A shaping box comprising top and bottom plates provided with apertures to receive a pulley band, one of said plates being hingedly mounted, a curved arm pivotally mounted on each of said top and bottom plates and in sealed engagement therewith, a tail 40 piece on one of said arms extending across said box between said plates and terminating in a bifurcated portion, and a tail piece on the other arm engaging said bifurcated portion.

45 Signed at Detroit, county of Wayne, State of Michigan, this 21st day of February, 1929.
ADRIAN O. ABBOTT, JR.
